UNITED STATES PATENT OFFICE.

HENRY CHISHOLM, OF NORTH RANDALL, OHIO.

AUTOMOBILE-STARTER.

1,246,233.

Specification of Letters Patent. Patented Nov. 13, 1917.

Application filed March 6, 1915. Serial No. 12,497.

To all whom it may concern:

Be it known that I, HENRY CHISHOLM, a citizen of the United States, residing at North Randall, in the county of Cuyahoga and State of Ohio, have invented a certain new and useful Improvement in Automobile-Starters, of which the following is a full, clear, and exact description.

This invention relates to mechanism, which is operable by a person in the driver's seat of an automobile, for cranking the internal combustion motor of said automobile.

The objects of the invention are to provide a mechanical starter which is of comparatively small first cost; which may be applied to conventional automobiles quickly and cheaply and with substantially no change in the construction of the automobile itself; which will be easily operable when in place; and which is not likely to get out of order.

With these objects in view, the invention consists in the construction and combination of parts shown in the drawings, and herein-after described and definitely pointed out in the appended claims.

In the drawings, Figure 1 is a side elevation, partly sectioned, of this invention applied to a motor car; Fig. 2 is a plan view of the same; Fig. 3 is a sectional end view in the plane of the line 3—3 on Fig. 1; Fig. 4 is a sectional end view in the plane of line 4—4 on Fig. 2.

In the drawings, 10 represents a part of an internal combustion motor, and 12 represents the crank shaft of said motor. 14 represents the cranking shaft, which is rotatably mounted in the bearing bracket 17, and is under the influence of a spring 18 tending to move said shaft endwise forward in its bearing. On the adjacent ends of these two alined shafts are the two members of a well known one way acting clutch. That is to say, the cranking shaft has on its rear end a concentric row of undercut teeth 15, and the crank shaft has a flange carrying one or more inwardly projecting pins 13.

The above described mechanism is conventional construction, and is to be found on nearly every automobile whose motor has to be cranked by hand. The specific construction shown is that which is found on the Ford automobile.

The starter includes a spirally twisted bar 20, and a member 21, which is shown in

the form of a cylinder. One of these parts must be movable endwise relatively to the other, and the endwise movable member must be incapable of rotation. As shown, it is the bar 20 which is so movable endwise, 60 and does not rotate. The other of said two parts must be rotatable, but incapable of endwise movement.

In the construction shown, the cylinder 21 is a rotatable member, and this is mounted in bearing brackets 31—32, which project upward from a base member 30, which must be securely fastened to some fixed part of the automobile. In the construction shown, this base member is secured in a horizontal position to the motor 10 by the same bolts 33 which are utilized to secure the head plate 11 to that part of the motor in which the cylinders are.

The cylinder 21 has near its front end an anti-friction thrust bearing 34 of familiar form against which a flange 23 on the cylinder engages. There is fixed to the front end of this cylinder a sprocket wheel 24. A coöperating sprocket wheel 19 is fixed to the cranking shaft 14, and these two are connected by a suitable chain belt 22.

Within the cylinder 21 and adjacent to the rear end thereof are two studs 26, on which two friction rollers 27 are mounted in such position as to engage sides of the bar 20 and near opposite edges thereof. Lugs 28 project inward from the inner periphery of said cylinder adjacent to opposite sides of said twisted bar 20, and adjacent to the two friction rollers 27, the function of these lugs being to prevent the cylinder 21, and its two friction rollers 27, from moving out of operative relation to the twisted bar 20.

Rigidly fixed to the rear end of twisted bar 20 is an operating bar 40, which extends through a suitable hole in the dash 41, and this bar has at its front end a pedal piece 42 for the operator to put his foot against.

Just in front of the dash 41 and adjacent to the rear end of the twisted bar the base member 30 is provided with a forked bracket 35 between the forks of which the operating bar 40 passes. One friction roller 36 is rotatably mounted between said forks, and the bar 40 rests upon it. Another friction roller 37 is mounted on a vertical axis on one fork and engages against one side of the operating bar 40, but near the lower edge thereof. Another friction roller 38 mounted on the 110

other fork of said bracket engages said operating bar 40 on the opposite side thereof but near its upper edge. These two friction rollers 38—37 take the strain from the 5 twisted bar 20 and serve to prevent it and the operating bar 40 from rotating while permitting their endwise movement.

When the operating bar 40 to which the twisted bar 20 is attached has been moved 10 rearward, the operator sitting in the driver's seat puts his foot upon the pedal piece 42 and pushes said bar rapidly forward. This causes the twisted bar to enter the cylinder, and by engaging the two friction rollers 15 27 causes said cylinder to turn. This turning movement is transmitted through the two sprocket wheels 24 and 19 and the chain belt 22 to the cranking shaft 14. If at this 20 time the clutch 15 of this shaft is in operative engagement with the clutch member 13 of the engine crank shaft said crank shaft will necessarily be turned in the same manner as if the operator had taken hold of the 25 crank 16.

In order that the cranking shaft 14 may be moved rearward to cause the operative engagement of the clutch member 15 carried thereby with the clutch member 13 on the motor crank shaft, a bell crank lever 50 is 30 pivoted to an arm 51 fixed to the bracket 17. One arm of this lever engages the end of the hub of the sprocket wheel 19, which as stated, is fixed to the cranking shaft. To the 35 other arm of this lever a cable 52 is connected. This cable goes over a guide sheave 53 mounted on the base member 30, and thence rearward, and its rear end is connected with one arm of a lever 54. This lever is pivoted on a vertical axis to one of the 40 forks of the bracket 35, so that as shown, its otherwise free end lies normally close to one side of the bar 40. On this side of said bar is a cam-faced lug 43 which, when bar 40 is drawn forward, preparatory to that rearward movement which is to turn the cylinder 21, will engage the lever 54, and so rock it that the cable will be drawn rearward. This 45 will rock lever 50 in such wise that the cranking shaft 14 will be moved rearward 50 to cause its clutch member to engage the clutch member on the motor crank shaft.

The forward movement of the bar 40 carries the lug 43 out of engagement with the lever 54. This allows the spring 18 to move 55 the cranking shaft forward; and said shaft will so move and thereby the clutch members 13 and 15 will be disengaged, as soon

as the engine crank shaft runs ahead of the cranking shaft 14.

The sprocket 19 may be connected with the 60 cranking shaft 14 by a one way acting ratchet clutch 60 of familiar form; and therefore, if one chooses, he may by manipulating the crank 16, crank the engine in the usual way without causing any movement of 65 the mechanical starting mechanism above described.

In order that the operator may be able to easily draw the bar 20—40 back to the starting position, a toe clip 62 may be fixed to 70 the rear end of the bar 40, as shown.

Having described my invention, I claim:

1. In an automobile starter, the combination of a base member adapted for connection with the fixed part of an automobile, bearings thereon, a cylinder rotatably mounted in said bearings and having inwardly projecting studs, friction rollers mounted on said studs, inwardly projecting lugs alongside of said rollers, a spirally twisted bar 80 whose front ends project into said cylinder in such wise that its edges project between said lugs and rollers, an operating bar rigidly fixed to said spirally twisted bar, guiding means for said operating bar causing it 85 to move in straight lines endwise, and a train of mechanism for transmitting rotary motion from said cylinder to the crank shaft of the motor.

2. In an automobile starter, the combination of a cylinder rotatably mounted, a thrust bearing for the front end of said cylinder, inwardly projecting studs near the rear end of said cylinder, friction rollers mounted upon said studs, a spirally twisted 90 bar whose front end projects into said cylinder and into engagement at its sides with said rollers, an operating bar rigidly fixed to the said twisted bar and projecting rearward therefrom, a roller below said bar and 95 upon which the bar rests, and two rollers on opposite sides of the bar one engaging with one side of the bar near its upper edge, and the other with the other side of the bar near its lower edge, and a train of mechanism for 100 transmitting rotary motion from said cylinder to the crank shaft of the motor.

In testimony whereof, I hereunto affix my signature in the presence of two witnesses.

HENRY CHISHOLM.
